Attorney

UNITED STATES PATENT OFFICE.

NELSON B. WALDRON, OF LEWISTON, MAINE.

CENTRIFUGAL PUMP.

1,361,938.

Specification of Letters Patent. Patented Dec. 14, 1920.

Application filed December 23, 1918. Serial No. 267,890.

To all whom it may concern:

Be it known that I, NELSON B. WALDRON, a citizen of the United States, residing at Lewiston, county of Androscoggin, State of Maine, have invented certain new and useful Improvements in Centrifugal Pumps, of which the following is a specification.

This invention relates to pumps, my present improvements being directed to the increase in capacity of flow of such pump which forms the subject of my previous Letters Patent No. 1,189,889, dated July 4, 1916.

In the operation of such pump at high speed, even where the flare of the pump is comparatively slight, there is a considerable thinning of the water as it approaches the top of the rotary member. This decrease in depth now appears to have a relation to the flow at the lip. With the object therefore of increasing the rate of lip flow and hence actual delivery I have devised my present invention in which I provide for the maintenance of a substantially uniform depth during the rise of the water, and I secure an increased acceleration in the discharge.

In the embodiment employed this is accomplished by a tapering of the ribs, this being a simple and satisfactory form and hence employed for the purposes of illustrating my invention. It is to be understood, however, that this form is employed as illustrative. Throughout the specification and drawings like reference characters are correspondingly employed, and in the drawings:

Figure 1 is a central vertical section of a pump in accordance with my invention, and

Figs. 2 and 3 are transverse sections on the lines 2—2 and 3—3 of Fig. 1.

I have indicated at 1 an elevating member consisting of an open-ended shell of suitable length, which is continuously and uniformly flared upwardly, and is made fast, as by the spiders 2, to a shaft 3 that is journaled in suitable bearings 4. Shaft 3 is rotated from any suitable power source, as the motor 8, by any suitable power transmitting connections, as the sheave 5 on shaft 3, belt 6 and sheave 7 geared to the shaft of 50 the motor.

The lower intake end of the shell is provided with an inturned flange 9 which functions to support the water entering the shell until it has acquired sufficient momentum 55 to rise within the shell.

In order to prevent any considerable thin-

ning of the water as it approaches the upper discharge end of the shell, and to maintain substantially uniform depth of water during its rise, I interrupt the otherwise continuously smooth internal face of the shell above the intake by an arrangement of ribs which bears a definite relation to the intake and to the delivery of the water and which secures a marked increase in the efficiency of the pump.

For the purposes of this application I have illustrated the shell as having a plurality of internal, vertically disposed, spaced ribs 10, which taper upwardly from substantially a point at the intake to relatively considerable width at the discharge end of the shell. The depth of the ribs is preferably equal to the width of the flange 9, and is constant throughout their length, and the sides 75 11 of the ribs preferably slope inwardly on substantially radial lines.

The total width of all the ribs, that is, the sum of the distances between their sides 11 at the discharge end of the shell is 80 preferably equal to the difference in circumference of the shell at its intake and discharge ends. In other words, the taper of the ribs is proportional to the flare of the shell, so that the spaces or channels 13 between the ribs are of substantially the same 85 width and depth continuously along the shell.

By this arrangement, the water within the shell is kept at substantially constant depth 90 and is not permitted to spread or thin out as it approaches the discharge end of the shell, thus preserving the imparted momentum and securing increased rate of intake and accelerated discharge. The water or other fluid being pumped discharges into a spillway 12 at the upper end of the shell 1. It will be noted that the arms of the spiders 2 are attached to the ribs 10 themselves. This arrangement leaves the channels 13 100 between the ribs uninterrupted, so that the water may be freely raised. The increased efficiency of the present pump over prior pumps is believed due to the fact that the tapered ribs keep the water at constant 105 depth and prevent it from spreading out; that is to say, the ribs define a channel of uniform capacity from bottom to top of the shell, along which the water travels in a definite path. As will be evident, any tendency of the water to spread out over the extended surface introduces a factor of fric- 110

tion or "backlash," which reduces the momentum of the water. The tapered rib construction of the present invention prevents this spreading out tendency because the defined channel is of uniform capacity from bottom to top of the shell and offers no obstruction to the water in its travel from intake to delivery.

Various modifications in the form and 10 construction of my invention may obviously be resorted to if within the limits of the appended claims.

What I therefore claim and desire to secure by Letters Patent is:

- 15 1. A pump comprising an upwardly flaring rotatable elevating member having an inwardly projecting flange at its intake end, and having above said flange a plurality of upwardly tapering spaced ribs, effective to 20 counteract the tendency of the liquid to thin out as it approaches the discharge end of the elevating member.
- 25 2. A pump comprising a vertically disposed upwardly flaring rotatable elevating member having an inwardly projecting flange at its intake end, and having a plurality of vertically disposed spaced ribs tapering upwardly from substantially a point at 30 said flange to relatively considerable width at the discharge end of the elevating member and effective to counteract the tendency of the liquid to thin out as it approaches the discharge end of the elevating member.
- 35 3. A pump comprising a vertically disposed upwardly flaring rotatable elevating member having an inwardly projecting flange at its intake end, and having a plurality of vertically disposed spaced ribs tapering upwardly from substantially a point at 40 said flange to relatively considerable width at the discharge end of the elevating member and effective to counteract the tendency of the liquid to thin out as it approaches the discharge end of the elevating member, the total width of the ribs at the 45 discharge end of the elevating member being substantially equal to the difference in circumference at the intake end and discharge 50 ends of the shell.
4. A pump comprising a vertically disposed upwardly flaring rotatable elevating member having an inwardly projecting

flange at its intake end, and having a plurality of vertically disposed spaced ribs tapering upwardly from substantially a point at said flange to relatively considerable width at the discharge end of the elevating member and effective to counteract the tendency of the liquid to thin out as it approaches the discharge end of the elevating member, the total width of the ribs at the discharge end of the elevating member being substantially equal to the difference in circumference at the intake end and discharge 65 ends of the shell, and the sides of the ribs sloping inwardly on substantially radial lines.

5. A pump comprising an upwardly flaring rotatable elevating member having an inwardly projecting flange at its intake end, and having above said flange a plurality of upwardly tapering spaced ribs, the depth of the ribs at the discharge end of the elevating member being substantially equal to the width of said flange.

6. A pump comprising an upwardly flaring rotatable elevating member having a plurality of upwardly tapering spaced ribs, the flare of the elevating member and the taper of ribs being substantially equal so that the spaces or channels separating the ribs are of substantially the same width and depth continuously along the elevating member.

7. A pump comprising an upwardly flaring vertically disposed rotatable shell having a series of vertically disposed spaced channels of substantially the same width and depth continuously along the shell.

8. A centrifugal pump, comprising an upwardly flaring rotatable elevating member having a plurality of upwardly tapering spaced ribs providing continuous channels for the passage of the fluid being pumped, a shaft arranged within said elevating member, and means carried by said shaft and attached to said ribs for rotatably connecting said shaft and elevating member.

In testimony whereof I affix my signature 100 in presence of two witnesses.

NELSON B. WALDRON.
